MULTIPLE EXPANSION ENGINE

Samuel Lippincott Griswold Knox, Englewood,
N. J.

Application January 12, 1939, Serial No. 250,623

14 Claims. (Cl. 121—111)

This invention relates to multiple expansion engines which are operated by the pressure of elastic fluids such as steam and in its more specific aspects to a system of steam distribution and auxiliary relief for compound engines of the steam reverse type.

As conducive to a clearer understanding of the instant invention, reference is had to my prior Patent 1,845,288, granted February 16, 1932, which discloses a simple steam reverse engine designed to permit early cut-off. In such an engine a plurality of cylinders and a like number of valves are proposed, three cylinders and three valves being illustrated. As distinguished from older types of steam reverse engines in which each valve worked in conjunction with a particular cylinder, each valve works in conjunction with two sets of ports, of which one set admits steam to one cylinder and another set admits steam to a different cylinder. Thus for a three-cylinder engine, cut-off can be accomplished at approximately one-third of the stroke. For such a simple steam-reverse engine distribution of the steam may be effected in simple manner, as by the use of a double throttle or two throttle valves, steam being supplied by one throttle to those ends of all three valves which cause forward rotation, and by the other throttle to those ends of all three valves which cause reverse rotation. One such throttle valve arrangement is described and claimed in my prior Patent 1,850,209, dated March 22, 1932.

With a compound steam reverse engine incorporating the principles of early cut-off, as above discussed, complexities in distribution arise due to the fact that steam is admitted to the high pressure cylinder, from there passes to the receiver, and from the receiver goes to two low pressure cylinders so that the relatively simple distribution means of my above referred to patent is not feasible in a compound engine of the reversing type.

The present invention contemplates the provision of a novel system of steam distribution for a compound reversing engine having three cylinders and three valves by which steam is sent to those ends of all three valves and related ports which cause forward rotation, and to the same valves and ports, but with a different grouping thereof, for reverse rotation. More specifically, the present invention provides a system of steam distribution including a distributing valve by which a compound engine of the type under discussion may be reversed, the steam exhausting from the high pressure cylinder into the receiver

being carried back to the distributing valve and passing through it, being directed through one set of canals leading from the distributing valve for one direction of rotation and through another set of canals from the distributing valve for the other direction of rotation.

In a compound engine of the character under consideration, all cylinders are usually provided with uniflow exhaust ports. The high pressure cylinder exhausts through these uniflow ports into the receiver; the low pressure cylinders exhaust through their uniflow ports either to the atmosphere or to a condenser. However, if such were the only means of exhausting steam from the cylinders, a low weight efficiency from the engine would be obtained, because as soon as the piston on its return stroke closes the uniflow ports, steam will be trapped in the cylinder and thereupon compressed far above the admission point, unless excessive clearance is provided, thereby increasing the stresses on the engine and pumping steam back into the main feed-line with no advantage. For this reason, ordinary uniflow engines are frequently provided with additional exhaust ports which remain open much longer than the uniflow ports, eccentrics or cams and other mechanism of complicated nature being provided for their operation.

The present invention contemplates a system of auxiliary relief which does away with the requirement of eccentrics and like mechanism and, instead, uses the valves in conjunction with the one set of ports which do not control the direction in which the engine is running at the moment to provide auxiliary relief for that direction of rotation. Thus the desirable auxiliary relief is obtained with no extra parts whatever. With the engine running in one direction, instead of exhaust ceasing as soon as a piston returns a short distance from the exhaust end of its stroke and so cutting off access of the steam trapped in the cylinder to the uniflow ports, the reverse ports from another valve connected with that same cylinder for operation of the engine in opposite direction open after the uniflow ports are closed and before there occurs objectionable compression of the steam trapped in the end of the cylinder into which the piston is moving. As the reverse ports for the high pressure cylinder are connected to the receiver through the valve of the distributing system, the invention provides that the auxiliary exhaust from the high pressure cylinder goes to the receiver, just as does the main exhaust, through the uniflow ports, and

that the auxiliary exhaust from the two low pressure cylinders goes to exhaust.

Other objects will be in part obvious and in part hereinafter pointed out in connection with the following analysis of this invention wherein is illustrated an embodiment of the invention in detail.

In the drawings—

Fig. 1 is a transverse section of a compound steam reverse engine in accordance with the invention, the section being taken through the port at the crank end of the engine which admits steam from one of the valves (valve *a*) to the high pressure cylinder;

Fig. 2 is a section generally along lines 2—2 of Fig. 1, the detail of the crank shaft, connecting rods, cross heads and the like being omitted as they form no part of the present invention;

Fig. 3 is a diagrammatic section view of the cylinders and valves illustrating the connections between the valves and cylinders for both directions of rotation;

Fig. 4 is a schematic diagram illustrating the path of steam distribution for one direction of rotation of the engine;

Fig. 5 is a schematic diagram illustrating the path of steam distribution for opposite rotation, or operation in reverse direction, of the engine;

Fig. 6 is a schematic diagram illustrating the distributing canals between the distributing valve and the cylinder valves;

Fig. 7 is an imaginary section through the cylinder valves and cylinders, being developed so that the center lines of the valves and cylinders lie in the same plane, and further illustrating, respectively, the relations of the pistons, valves, and eccentrics.

Referring now to the drawings wherein like reference characters designate like parts throughout the several views, the compound steam reverse engine in accordance with the present invention utilizes a high pressure cylinder C conventionally arranged intermediate the low pressure cylinders A and B, the relative location of the cylinders being indicated in Fig. 1. Arranged in the cylinder block 5, and at a convenient location therein are the valve chests of the valves *a*, *b* and *c* related to the cylinders as indicated, and also the valve chest of a distributing valve *d*, which latter is disposed side-wardly of the valve *a*. A cover plate 10 is suitably secured across the top of the cylinder block and forms therewith an enclosure providing a receiver space through which extends the chests of the valves *a*, *b*, *c*, *d*. The head ends of the valve chests for the valves *a*, *b* and *c* is provided with suitable manifold caps or covers (not shown) which carries steam to the ends of valves *a*, *b* and *c*. As above indicated, Fig. 1 is a section taken through one of the ports at the crank end of the engine which connects the valve *a* and the high pressure cylinder C and through a transversely aligned port which connects either of the valves *b*, *c* with cylinder B. Due to difficulty in illustrating, the distributing canals between valve *d* and the cylinder valves *a*, *b* and *c* are not shown in Fig. 1, but are schematically shown in the succeeding figures to be referred to.

In Fig. 2 the distributing valve and the cylinder valve *a*, together with the chests in which they operate, are shown in section, the valve *b* being shown partly in elevation. Each cylinder is provided with uniflow exhaust ports inter-

mediate its ends, of which the uniflow exhaust ports Bx of cylinder B are shown.

The valves *a*, *b* and *c* are operated through valve stems 15 in conventional manner by eccentrics (not shown) which may either be mounted on the engine crank shaft or on a separate shaft driven by the crank shaft synchronously therewith. The piston rods 17 of pistons PC, PB and PA drive the engine crank shaft in either forward or reverse direction, depending on the direction of rotation of the engine. As the cranks, connecting rods, cross heads, and like parts through which the valve stems and piston rods are connected to crank shaft and eccentric shaft, if separate eccentric shaft is used, may be regarded as conventional, no detailed description will be here given of such parts, it being understood, however, that the valve eccentrics (or cranks) are 120° apart, the cylinder cranks are 120° apart, and that each valve eccentric has suitable angular relationship with the crank of the cylinder which it operates for forward and reverse rotation, as typically illustrated in Fig. 7 to be referred to hereinafter.

The cylinder valves *a*, *b*, *c* may take various forms and may also partake of various motions. In the illustrated embodiment, which may be taken as exemplary of one type of valve which provides satisfactory operation, the valves *a*, *b* and *c* are of tubular or sleeve-like form, open from end to end, and are given straight reciprocatory motion by the stems 15 secured to the valves adjacent their crank ends. The outer diameter of the intermediate portion of each valve is reduced, thereby to provide, in conjunction with its encircling sleeve 19, an annular steam space 18 of substantial length. The valves each operate in the sleeve 19, the sleeves being press-fitted into bored holes in the walls which make up the cylinder block casting. The arrangement is such that steam admitted to an end of the valve may pass through the interior thereof to the other end, and that steam admitted to the annular space 18 between the valve and its fixed sleeve 19 may pass the length of said space.

The distributing valve generally indicated at *d* operates in a sleeve 20 press-fitted into the cylinder block casting. Sleeve 20 is of substantial length and is provided along its length with a plurality of annular series of openings 21, 22, 23, 24, 25, 26, 27. The central openings 24 register with the boiler-steam supply opening 30 into which a steam line from the boiler is adapted to be connected. Sleeve openings 21—23 inclusive and 25—27 inclusive register with annular channels in the valve chest forming a part of the cylinder block, of which channels 22a and 26a communicate directly with the receiver space; channels 23a and 25a communicate with canals running to valves *a* and *c*, respectively; channel 21a communicates with a canal running to valves *b* and *c*; and channel 27a communicates with a canal running to valves *a* and *b*, all as will be described hereinafter.

The valve proper consists of a plurality of pistons which, in the construction shown, are four in number, the pistons being suitably spaced from each other and being rigidly secured to a stem 29 which extends through the center of the pistons. The spacing between the valve pistons is such that in the mid or neutral position of the valve the adjacent faces of the intermediate valve pistons 31, 32 provide a passage generally in alignment with steam inlet opening 30 and sleeve openings 24. The length of each of

the pistons 31, 32 is such that they cut off communication between sleeve openings 24 and adjacent openings 23, 25, whereby no steam can flow to either of said openings. The left-end 5 piston 33, when the valve is in its neutral position, serves to cut off communication between the channel 22a going to the receiver and the channel 21a delivering to valves b and c. Similarly, the right-end piston 34 cuts off communication 10 between the channel 26a going to the receiver and the channel 27a delivering to valves a and b.

To the left-end piston 33 is secured a yoke 35, to which is connected one end of a link 36, the 15 other end being secured as by a pin 37 to operating shaft 38, which can be rocked throughout a limited arc to either side of its mid or neutral position. The shaft 38 is adapted to be rocked by a handle (not shown) under the control of 20 an operator, rocking movement in one direction causing movement of distributing valve d to the left for reverse rotation of the engine, with rocking movement in opposite direction actuating valve d to the right thereby to cause forward 25 operation of the engine.

Considering now the arrangement of ports between valves a, b, c and cylinders A, C, B, the compound engine under description incorporates the principles disclosed in my prior Patent 30 1,845,288 in that it provides two sets of ports in conjunction with each valve, one set of ports admitting steam to one cylinder, and the other set of ports admitting it to a different cylinder. Application of this principle to a compound engine 35 will be apparent from Fig. 3, such being a valve, cylinder and port diagram looking into the head end of the cylinders.

Valves a, b and c are arranged, respectively, above the cylinders A, C, and B, of which the 40 high pressure cylinder C is arranged intermediate the low pressure cylinders A and B. For operation of the engine in one direction (reverse direction), valve a supplies steam to the high pressure cylinder C through outside port aC; valve b supplies steam to low pressure cylinder A 45 through the outside port bA; and valve c supplies steam to low pressure cylinder B through outside port cB.

From the aforesaid designation of ports as 50 "outside ports," it is to be understood that for the particular engine under description steam is supplied to the respective cylinders for reverse operation through a set of outside ports. In addition to such outside ports, valves a, b and c 55 are connected to cylinders A, C and B through a set of "inside ports" aA, bB and cC, which act as auxiliary relief ports during reverse operation of the engine, and through which steam is supplied to the cylinders for forward operation. 60 During forward operation, the outside ports aC, bA and cB act as auxiliary relief ports. The features of auxiliary relief of the cylinders A, C and B through inside ports aA, bB and cC, during reverse rotation, and of auxiliary relief of the 65 cylinders through outside ports aC, bA and cB during forward operation will be discussed hereinafter.

Reference has been made previously to the fact that in a simple engine as disclosed in my 70 Patent 1,845,288, it is only necessary to employ a double throttle valve, or two throttle valves, for distributing the steam to those ends of all three valves which cause forward rotation or to those ends of all three valves which cause reverse rotation. In a compound engine, however, due to

the fact that the high pressure cylinder exhausts to the receiver and that receiver steam is supplied to the low pressure cylinders, such an arrangement is not feasible and accordingly a distributing valve, such as the valve d, above referred to, is utilized in conjunction with a system of steam canals to obtain the desired reversal of operation. Such a system of distribution for reverse engine operation is diagrammatically illustrated in Fig. 4, wherein d is the 10 distributing valve which directs boiler steam through canal 2 to valve a which supplies cylinder C through outside port aC. Cylinder C exhausts through uniflow exhaust ports to receiver R, from whence the steam passes through canal 3 back to distributing valve d, which directs it through canal 4 to valve b, and also through canal 15 to valve c. From valve b steam passes to low pressure cylinder A through outside port bA, and from valve c steam passes to cylinder B 20 through outside port cB.

Referring now to Fig. 5, such being a diagrammatic representation of the steam distribution with the engine operating in forward direction, boiler steam is sent by distributing valve d to 25 valve c through canal 6, and from valve c passes to high pressure cylinder C through inside port cC. Exhaust from cylinder C passes to receiver R, from whence it returns to distributing valve d through canal 7, valve d then directing the steam 30 through canal 8 to valve a and through canal 9 to valve b. Steam from valve a passes to cylinder A through inside port aA, with steam from valve b passing to cylinder B through inside 35 port bB.

It will be appreciated from the foregoing that there is provided a system of distribution whereby steam exhausting into the receiver from the high pressure cylinder is returned to and through the distributing valve, with the distributing valve 40 thereupon directing steam through one set of ports to the cylinders for operation of the engine in one direction and through another set of ports for operation of the engine in the reverse direction.

Referring to Fig. 6 wherein is illustrated a typical system of canaling between the distributing valve d, as illustrated in Fig. 1, and the cylinder valves a, b and c, the distributing valve d is shown in its left position which, in the construction illustrated, will cause the engine to operate in reverse direction. Valve piston 31 is in position to establish communication between steam inlet 30 and channel 23a, into which opens one end of canal 2 referred to in Fig. 4, the other 50 end of the canal opening into the end of valve a and supplying high pressure steam thereto. Similarly, valve piston 33 has established communication between the channel 22a which opens to receiver (line 3 in Fig. 4 indicates this connection) and channel 21a into which opens one end of the combined canals 4, 5, the other or branched ends thereof delivering to the outer ends of both valves b and c, whereby receiver steam may be supplied to valves b and c. Valve piston 32 is in 55 position closing communication between boiler steam opening 30 and channel 25a with which canal 6 to the inside of valve c connects, and, similarly, valve piston 34 is in position closing communication between channel 26a which opens 60 to receiver (see line 7, Fig. 5) and channel 27a with which connects the canals 8 and 9 running to the inside of valves a and b. The path of steam flow as above described is indicated by the full line arrows in Fig. 6.

Full movement of distributing valve *d* to the right results in operation of the engine in forward direction, by supplying boiler steam through canal 6 and inside of valve *c* to the high pressure cylinder C, and by supplying low pressure cylinders A and B with steam from the receiver through canals 8 and 9, to the inside of valves *a* and *b*, respectively. The path of steam flow for forward rotation is indicated by the dot-dash arrows.

Referring now to Fig. 7, such being a schematic layout of the valves, pistons, and their connecting rods and eccentrics developed to illustrate the relation of piston and valve position to port location, the piston PA of the low pressure cylinder A is moving to the left, the eccentrics moving anti-clockwise for reverse direction, as indicated by the full line arrows related to each of the connecting rods. As will be seen from the position of valve *b* which supplies steam to cylinder A for reverse rotation, right-hand admission is taking place through righthand outside port *bA*, the valve *b* closing righthand inside port *bB* and lefthand outside port *ba*. Valve *b*, however, has opened lefthand inside port *bB* leading to cylinder B, as will be referred to hereinafter.

Piston PC is moving to the right, its valve *a* for reverse rotation moving to the left, and having just cut off lefthand admission through lefthand outside port *aC*. Righthand outside admission port *aC* is closed, but righthand inside port *cC* will open shortly as valve *c* is moving towards the right.

Piston PB is moving towards the left with its valve *c* for reverse rotation moving to the right. Piston PB is approaching the end of its stroke, the righthand and lefthand outside admission ports *cB* being both closed by valve *c*. Since piston PB has closed the uniflow exhaust ports, it would normally compress the steam trapped between its working face and the head end of the cylinder, but the auxiliary relief to be described functions to prevent this condition.

The Fig. 7 illustration also provides basis for describing the forward operation of the engine, for which the eccentrics move clockwise as indicated by the dotted line arrows related to the associated connecting rods.

Piston PA moving to the right is substantially at the end of its exhaust stroke, with admission about to take place through the righthand inside port *aA*, with its valve *a* for forward rotation moving to the right. All other ports are closed.

Piston PC of the high pressure cylinder C is moving to the left toward the exhaust end of its stroke, its valve *c* for forward rotation, which is moving to the left, having cutoff admission through righthand inside port *cC*. Righthand outside port *aC* is closed by valve *a*, left-hand inside port *cC* is closed by valve *c*, and lefthand outside port *aC* is closed by valve *a* but will open shortly as valve *a* is moving to the right.

Piston PB of the low pressure cylinder B is moving to the right and is still receiving steam through the lefthand inside port *bB*, its valve *b* for forward rotation moving towards the right and about to cut off admission. All other inside and outside ports are closed.

By further reference to Fig. 7, it will be seen that the canals leading from and to the distributing valve *d* (not shown in this figure) have been indicated in their approximate position so as to supply steam to the ends of the valves *a*, *b* and *c* for reverse operation, and to the inside of said valves for forward operation of the engine. Thus

canal 2 delivers to the end of valve *a*, with canals 4, 5 delivering to the ends of valves *b* and *c*, respectively, as in Figs. 4 and 6. In like manner, canal 6 is shown as delivering steam to the inside of valve *c* (space 18), canal 8 is delivering to the inside of valve *a*, and canal 9 to the inside of valve *b*, all as indicated in Figs. 5 and 6.

Considering now the exhaust features of a compound engine as described, each of the cylinders is provided with uniflow exhaust ports (see Fig. 10 7), exhaust ports *Cx* from the high pressure cylinder C leading directly into the receiver space, and uniflow exhaust ports *Ax* and *Bx* from the low pressure cylinders A and B going to atmosphere or condenser. As pistons PC, PA and PB move 15 toward the exhaust end of their respective strokes, they cover their uniflow exhaust ports so that if such ports were the only means provided to exhaust steam from the cylinders, steam would be trapped in that portion of the cylinders into 20 which the pistons are moving. Usually, uniflow engines of the character under consideration are provided with additional exhaust ports which remain open much longer than the uniflow ports, the additional exhaust ports requiring eccentrics 25 and other mechanism for their operation.

The present invention provides auxiliary relief of cylinders A, B and C by the same means which effect steam distribution as aforesaid. Thus, valves *a*, *b* and *c* act in conjunction with the one 30 set of the ports and canals through which steam is not being admitted to the cylinder for a given direction of operation as auxiliary relief means for that direction of engine operation. For example, if the engine is running in reverse, steam 35 being accordingly supplied by valves *a*, *b* and *c* to cylinders C, A and B, respectively, through outside ports *aC*, *bA* and *cB*, the arrangement is such that auxiliary relief is provided through the valves, canals and the inside ports which constitute the distributing means to the cylinders for forward operation. Similarly, if the engine is operating in forward, auxiliary relief is provided through the valves, canals and outside ports 40 through which the steam is distributed for reverse operation.

The arrangement will be understood from an analysis of the Fig. 6 diagram, where it will be remembered valve *d* is in its lefthand position for reverse operation of the engine, in which position valve *a* supplies steam to cylinder C through outside port *aC*; valve *b* supplies steam to low pressure cylinder A through outside port *bA*; and valve *c* supplies steam to low pressure cylinder B through outside port *cB*. Under this condition 55 of operation, auxiliary relief for the cylinders is obtained as follows:

Auxiliary relief for the high pressure cylinder C is obtained through inside port *cC*, valve *c* and thence to the receiver through canal 6, distributing valve *d*, and channel 26a which opens to receiver, as indicated by the dotted line arrows. Auxiliary relief for low pressure cylinder A is provided through inside port *aA*, valve *a*, canals 8, 9, and distributing valve *d* whose right end 65 opens to exhaust. Auxiliary relief for low pressure cylinder B is provided through port *bB*, valve *b*, canals 8, 9, distributing valve *d*, and similarly to exhaust. The paths of auxiliary relief from cylinders A and B are also indicated with dotted 70 line arrows.

With the valve *d* in its righthand position for forward operation, auxiliary relief for high pressure cylinder C is provided through outside port *aC*, valve *a*, canal 2, distributing valve *d* to the 75

receiver. Auxiliary relief for the low pressure cylinder A is provided through outside port *bA*, valve *b*, canals 4, 5, distributing valve *d*, and thence to exhaust through the left end of the distributing valve. Auxiliary relief for the low pressure cylinder B is provided through outside port *cB*, valve *c*, canals 4, 5, and similarly to exhaust through distributing valve *d*. The path of steam flow for auxiliary relief of the cylinders when the engine is operating in forward direction is indicated by the "dash X" arrows appearing in Fig. 6.

The manner in which valves *a*, *b* and *c* operate in conjunction with the inside and outside ports to provide such auxiliary relief will be further realized from a consideration of Fig. 7. Referring to Fig. 7, it will be seen that for reverse operation piston PC is moving to the right and has covered the uniflow exhaust ports *Cx*, with valve *c*, which would control admission to cylinder C if the engine were operating in forward direction, moving to the right. Some further movement of valve *c* in that direction will uncover righthand inside port *cC*, the arrangement being such that the said inside port *cC* will be uncovered upon piston PC completing about two-thirds of its stroke. When so uncovered, auxiliary relief is provided through the inside of valve *c*, canal 6 and to receiver.

In Fig. 7 piston PB, which is moving to the left towards the exhaust end of its stroke, would normally compress steam in the head end of the cylinder following closing of the uniflow exhaust ports *Bx*. However, valve *b*, which controls admission of steam to cylinder B for forward operation, has uncovered lefthand inside port *bB*, so that auxiliary relief of cylinder B is taking place through said inside port *bB*, valve *b*, canals 8, 9, valve *d*, to exhaust (see Fig. 6).

While cylinder A is obtaining no auxiliary relief in the Fig. 7 diagram, it will be understood that as piston PA nears the end of its lefthwise movement, valve *a* will uncover the lefthand inside port *aA*, to provide auxiliary relief through said inside port *aA*, valve *a*, canals 8, 9, distributing valve *d*, to exhaust.

For forward operation and with the piston PC of the high pressure cylinder C moving to the left and nearing the end of its exhaust stroke, cylinder C is about to receive auxiliary relief, as valve *a*, which is moving to the right, is about to uncover lefthand outside port *aC*, so that the cylinder may exhaust through canal 2 to the receiver. In like manner cylinder B will obtain auxiliary relief when its valve *c* for forward rotation, which is moving to the left, uncovers the righthand outside port *cB*. Cylinder A is obtaining auxiliary relief in its position as shown through righthand outside port *bA*, the valve *b* moving it the right shortly to cut off this auxiliary relief.

By reference to Figs. 3 and 7, it will be understood that each set of outside and inside ports at the ends of the valves has a common opening through the cylinder wall. From this common opening, the outside ports each branch outwardly toward the outer end of the valve, and the inside ports each branch inwardly towards the inside of the valve. Means other than a common opening for the related sets of ports may be utilized, such as individual openings but with the ports of a set connected intermediate their ends.

With the above arrangement, auxiliary or additional relief beyond that provided by the uniflow exhaust ports is provided so that no objectionable compression of steam in the end of

the cylinders into which the pistons are moving can occur, and the valves, ports, and canals which provide in the first instance the means for distributing steam to the cylinders for either forward or reverse operation of the engine also have the additional function of providing for auxiliary exhaust. Accordingly the weight efficiency of the engine (weight per horse power) is increased, the requirement for extra ports, parts or other mechanism to effect auxiliary relief is obviated, and simple and certain operation is assured.

While in the foregoing analysis of the invention, the relief of the cylinders obtained through the sets of ports and canals through which steam is not being supplied to the cylinders for a given direction of engine operation has been referred to and designated as auxiliary to the main or principal exhaust obtained through the uniflow exhaust ports, the sets of ports and canals as aforesaid may and can be utilized as the sole means of exhausting the cylinders, as in engines designed for specialized purposes where high speed is not of importance, and the claims are to be interpreted accordingly. It will also be expressly understood that the engine as described can be operated by the pressure of elastic fluids other than steam, and that where the word "steam" is used throughout the specification and in the claims, such use is made for convenience and is intended to designate and embrace all forms of elastic fluids capable of operating engines of the character herein described.

As many changes could be made in carrying out the above construction without departing from the scope of the invention, it is intended that all matter contained or shown in the accompanying drawings shall be interpreted as illustrative and not in a limiting sense.

I claim:

1. A compound steam reverse engine comprising a high pressure cylinder, a receiver into which the high pressure cylinder exhausts, a plurality of low pressure cylinders adapted to receive steam from the receiver, control valves each connected to the cylinders by two sets of ports, of which one set connects a valve to one cylinder and the other set connects the same valve to a different cylinder, each valve being so related to the ports connecting it with the cylinders as aforesaid as to supply steam to the cylinders through one set of ports only for one direction of engine operation and thru the other set of ports only for the opposite direction of engine operation, and distributing means operative to direct high pressure steam to the one of the two valves controlling the high pressure cylinder and receiver steam to the one of the two valves controlling each low pressure cylinder for the given direction of engine operation.

2. A compound steam reverse engine comprising a high pressure cylinder, a receiver into which the high pressure cylinder exhausts, a plurality of low pressure cylinders adapted to receive steam from the receiver, control valves each connected to the cylinders by sets of outside and inside ports, of which the outside ports connect a valve to one cylinder and the inside ports connect the same valve to a different cylinder, each valve being so related to the ports connecting it with the cylinders as to supply steam to the cylinders through one set of ports only for one direction of engine operation and thru the other set of ports only for the opposite direction of engine operation, and distributing means operative to direct high pressure steam to the one of the two

cylinders including a distributing valve, means for actuating the valve to one of two positions, and two sets of steam passages extending from the distributing valve to the control valves, the 5 distributing valve in one position directing through one set of passages high pressure steam to one of the two valves controlling the high pressure cylinder and receiver steam to the one of the two valves controlling each low pressure 10 cylinder for a given direction of engine operation, the distributing valve in its other position directing through the other set of passages high pressure steam to the other of the two valves controlling the high pressure cylinder and receiver steam to the other of the two valves controlling each low pressure cylinder for the opposite direction 15 of engine operation.

9. A compound steam reverse engine comprising a high pressure cylinder, a receiver into which 20 the high pressure cylinder exhausts, a plurality of low pressure cylinders adapted to receive steam from the receiver, the cylinders being each provided with uniflow exhaust ports, pistons operating in the cylinders, control valves each connected to the cylinders by two sets of ports, of which one set connects a valve to one cylinder and the other set connects the same valve to a different cylinder, each valve being operative to supply steam to the cylinders which it controls 25 through only one set of ports for a given direction of engine operation and through only the other set of ports for the opposite direction of engine operation, the arrangement being such that the sets of ports through which steam is not being supplied to the cylinders for the given direction of engine operation function as auxiliary relief ports. 30

10. A compound steam reverse engine comprising a high pressure cylinder, a receiver into which the high pressure cylinder exhausts, a plurality of low pressure cylinders adapted to receive steam from the receiver, the cylinders being each provided with uniflow exhaust ports, pistons operating in the cylinders, control valves each connected to the cylinders by two sets of ports, of which one set connects a valve to one cylinder and the other set connects the same valve to a different cylinder, each valve being operative to supply steam to the cylinders which it controls through only one set of ports for a given direction of engine operation and through 35 only the other set of ports for the opposite direction of engine operation, the arrangement being such that the sets of ports through which steam is not being supplied to the cylinders for the given direction of engine operation function as auxiliary relief ports. 40

11. A compound steam reverse engine comprising

ing a high pressure cylinder, a receiver into which the high pressure cylinder exhausts, a plurality of low pressure cylinders adapted to receive steam from the receiver, the cylinders being each provided with uniflow exhaust ports, 5 pistons operating in the cylinders, control valves each connected to the cylinders by two sets of ports, of which one set connects a valve to one cylinder and the other set connects the same valve to a different cylinder, each valve being operative to supply steam to the cylinders which it controls through only one set of ports for one direction of engine operation and through only the other set of ports for the opposite direction of engine operation, the arrangement being such that the sets of ports through which steam is not being supplied to the cylinders for the given direction of engine operation function as auxiliary relief ports for the cylinders, distributing means operative to distribute steam to the control valves, said means including a distributing valve movable to one of two positions and two sets of canals connecting the distributing valve and said control valves, the distributing valve in one position being operative to direct through 10 one set of canals high pressure steam to the one of the two valves controlling the high pressure cylinder and receiver steam to the one of the two valves controlling each low pressure cylinder for the given direction of engine operation, the distributing valve in its other position being operative to direct through the other set of canals steam to the other of said valves controlling the cylinders for the opposite direction of engine operation, said distributing valve being 15 also operative to connect the cylinders to a lower pressure stage through said ports when the latter function as auxiliary relief ports and through the set of canals through which steam is not being directed to the control valves. 20

12. A compound steam reverse engine comprising a high pressure cylinder, a receiver into which the high pressure cylinder exhausts, a plurality of low pressure cylinders adapted to receive steam from the receiver, pistons operating in the cylinders, control valves each connected to the cylinders by two sets of ports, of which one set connects a valve to one cylinder and the other set connects the same valve to a different cylinder, each valve being operative to supply steam to the cylinders which it controls through only one set of ports for one direction of engine operation and through only the other set of ports for operation in opposite direction, the arrangement being such that the sets of ports through which steam is not being supplied to the cylinders for a given direction of engine operation function as exhaust ports for the cylinders, and means operative to direct high pressure steam to the one of the two valves controlling the high pressure cylinder and receiver steam to the one of the two valves controlling each low pressure cylinder for the given direction of engine operation, said means being also operative to connect the cylinders to a lower pressure stage through said ports when the latter function as exhaust ports. 25

13. A compound steam reverse engine comprising a high pressure cylinder, a receiver into which the high pressure cylinder exhausts, a plurality of low pressure cylinders adapted to receive steam from the receiver, pistons operating in the cylinders, control valves each connected to the cylinders by two sets of ports, of which one set connects a valve to one cylinder and the 30

other set connects the same valve to a different cylinder, each valve being operative to supply steam to the cylinder which it controls through only one set of ports for one direction of engine operation and through only the other set of ports for operation in opposite direction, the arrangement being such that the sets of ports through which steam is not being supplied to the cylinders for a given direction of engine operation 10 function as exhaust ports for the cylinders, and means operative to direct high pressure cylinder and receiver steam to the one of the two valves controlling each low pressure cylinder for the given direction of engine operation, said 15 means being also operative to open the high pressure cylinder to the receiver and the low pressure cylinders to exhaust through said ports when the latter function as exhaust ports.

14. A compound steam reverse engine comprising a high pressure cylinder, a receiver into 20

which the high pressure cylinder exhausts, a plurality of low pressure cylinders adapted to receive steam from the receiver, pistons operating in the cylinders, control valves each connected to the cylinders by two sets of ports, of which 5 one set connects a valve to one cylinder and the other set connects the same valve to a different cylinder, each valve being operative to supply steam to the cylinder which it controls through only one set of ports for one direction of engine 10 operation and through only the other set of ports for operation in opposite direction, the arrangement being such that the sets of ports through which steam is not being supplied to the cylinders for a given direction of engine operation 15 function as exhaust ports for the cylinders, and means for distributing steam to the valves and thence to the cylinders.

SAMUEL LIPPINCOTT GRISWOLD KNOX. '20
